[57] CLAIM

The ornamental design for a flashlight body, as shown and described.

DESCRIPTION

FIG. 1 is a top plan view of the flashlight body of this invention;

FIG. 2 is a bottom plan view thereof;

FIG. 3 is a side elevational view thereof, the side opposite being a mirror image thereof;

FIG. 4 is an isometric view thereof, with the broken line showing for illustrative purposes only and forming no part of the claimed design;

FIG. 5 is a front elevational view thereof;

FIG. 6 is a rear elevational view thereof;

FIG. 7 is a top plan view of an alternative embodiment of the flashlight body of this invention;

FIG. 8 is a bottom plan view thereof;

FIG. 9 is a side elevational view thereof, the side opposite being a mirror image thereof;

FIG. 10 is an isometric view thereof;

FIG. 11 is a front elevational view thereof; and,

FIG. 12 is a rear elevational view thereof.
